UNITED STATES PATENT OFFICE.

MAXIMILIAN H. MOSKOVITS, OF KANSAS CITY, MISSOURI.

FURNACE-GRATE.

SPECIFICATION forming part of Letters Patent No. 407,873, dated July 30, 1889.

Application filed January 29, 1889. Serial No. 297,908. (No model.)

To all whom it may concern:

Be it known that I, MAXIMILIAN H. MOSKOVITS, of Kansas City, Jackson county, Missouri, have invented certain new and useful 5 Improvements in Furnace-Grates, of which the following is a full, clear, and exact description, reference being had to the accompanying drawings, forming a part hereof.

This invention relates to an improvement 10 upon Patent No. 382,104, granted to me May 1, 1888; and it consists in the novel construction and combination of the various parts, as will be more fully hereinafter specified.

In the drawings forming part of this specification, Figure 1 is a plan view of my improved grate. Fig. 2 is a front view of the same. Fig. 3 is a side view. Fig. 4 is a transverse section of one of the grate-bars, taken on the line $x x$ of Fig. 1; and Fig. 5 is a 20 detail view of the bearing.

Referring to the drawings, in which similar letters of reference indicate corresponding parts, A indicates one of my improved grate-bars, which consists of a series of parallel 25 zigzag webs $c c$, (usually three in number,) united at their ends with a web or end piece c' , and braced at suitable intermediate points by the connecting ribs or webs b , and a straight longitudinal supporting-web a , cast integral 30 with the under side of upper part at about the middle of the same and extending its entire length. The web a is connected with the central zigzag web c by the connecting-pieces a' , by which construction a series of holes or 35 apertures $h h$ are formed, through which air may be fed to the fuel upon the grate-bar. To prevent the accumulation of ashes, clinkers, and the like upon the web a , I bevel or cut away the same, as shown at l , Figs. 2 and 40 4, and I usually alternate such beveled parts, as most clearly shown in Fig. 2.

From the foregoing it will be seen that a grate-bar is formed which can be more cheaply and easily constructed, and one which can be 45 very quickly arranged in conjunction with the adjacent bars to form a complete grate.

The advantages of this construction over that shown in my Patent No. 382,104 are that only one supporting-web is necessary for three 50 zigzag webs composing a comparatively large

fire-surface. Heretofore the zigzag webs of grates have been made comparatively thick and heavy in transverse section, preventing the use of any great number of them in making up a fire-surface. This of course has 55 also operated to reduce the "air-space" and hinder combustion to a corresponding degree. In my improved grate a large fire-surface is provided by employing a minimum weight of iron, having ample air-space, and 60 yet its air-openings are sufficiently small to prevent dropping of fuel to the ash-pit. Thus it is that a fire-surface of a given area is provided with only one-third of the number of supporting-webs, and hence one-third 65 less obstruction is offered to the upward passage of air. Further, much less obstruction is offered to ashes and clinkers falling through the grate, and the improved construction, taken as a whole, resulting in better combustion 70 of fuel, decreased necessity for stirring the fire, and slight danger of burning the grate, which last fact is self-evident, as the quantity of iron to be kept cool is comparatively small and the air-space provided is 75 proportionately large. The small amount of iron required is perhaps best illustrated by the fact that in the older grates (where a supporting-web is provided for every zigzag web) the supporting-webs were only about one and 80 one-half inch apart, while in the present case they are separated fully four inches. In other words, a grate-surface of a given area now requires but one-third as many supporting-webs 85 as have heretofore been necessary.

The grate-bars A A are supported at each end upon a knife-edge bearing G, each bearing G working in an angular recess g' , formed in the under side of the end web-pieces $c' c'$.

It is of course obvious that the several bars 90 may be provided with any othersuitable form of end journals or bearings that will permit of imparting to them a rocking movement.

The knife-edge bearings G G are formed upon the upper sides of the supporting bars 95 or beams C C. Said bars, running parallel with the side walls of the fire-box and extending the entire length of the same, are securely held at their rear ends in the bridge-wall H, as clearly shown in Fig. 3. Whenever it is 100

deemed necessary, these supporting-bars C C may be braced by a cross-rod *d* and suitable nuts *d'*.

At a short distance forward of the bridge-
5 wall H the bars C C are provided with an up-
wardly-extending portion, to which is secured
the rigid zigzag grate-bar B, which forms the
extreme rear end of the grate.

To operate the rocking grate-bars, I employ
10 a rod E or E', said rod being secured at its
rear end between the vertically-depend-
ing lugs or ears *g g*, formed upon the under side
of the web *a*, and at its front end this rod is
pivotally connected with an operating-lever
15 D or D' at *e*, said levers being fulcrumed be-
tween the lugs *k* of the plate *f*. Of course,
however, the operating-levers may as well be
pivoted to the front plate of the furnace,
which would not change the operation and
20 results. The rod E is usually connected with
the front grate-bars, while the rod E' is con-
nected with the rear grate-bars. By this ar-
rangement I am enabled to operate one sec-
tion of the grate either independently of or
25 in conjunction with the other section, as may
be desired.

The operation of my device is as follows:
The fuel being fed in the usual manner, the
combustion is more complete at the rear part
30 of the grate, and the fuel will burn away
more rapidly. By operating the lever D the
front bars of the grate are rocked, feeding
the fresh fuel to the rear of the grate. The
air, entering the fire-box as usual, passes along
35 under the grate and through the zigzag open-
ings formed between the zigzag webs *c c*. The webs
a a, being perforated at *h*, allow
the air to pass freely through the fire-box and
up through the grate. Whenever it is de-
40 sired to shake the grate, the levers D and D'
are operated simultaneously, and the grate is

cleared of all ashes, clinkers, and the like.
The web *a*, being beveled, as shown and de-
scribed, prevents the ashes and clinkers from
accumulating upon the same, as is commonly
45 the case in other grate-bars.

Having thus described my invention, what I
claim, and desire to secure by Letters Patent,
is—

1. The improved grate-bar having an upper
fire-surface composed of a series of zigzag
webs *c c*, which are united at their ends,
the end web-pieces *c' c'*, and the lower straight
longitudinal supporting-web cast integral
with the upper zigzag webs and the end
55 pieces, said supporting-web being connected
with the series of zigzag webs by means of
connecting-pieces *a'*, whereby a series of air-
passages *h h* are formed between said upper
series of webs and the said supporting-web,
60 substantially as described.

2. The improved grate-bar having an upper
fire-surface composed of a series of zigzag
webs *c c*, which are braced at points interme-
diate of their lengths by short transverse
65 webs *b b* and united at their ends, the end
web-pieces *c' c'*, and the lower straight longi-
tudinal supporting-web cast integral with the
upper zigzag webs and the end pieces, said
supporting-web being connected with the se-
70 ries of zigzag webs by means of connecting-
pieces *a'*, whereby a series of air-passages *h h*
are formed between said upper series of webs
and the supporting-web, substantially as de-
scribed.

In testimony whereof I affix my signature in
presence of two witnesses.

MAXIMILIAN H. MOSKOVITS.
